Granger

[57] **CLAIM**

The ornamental design for a rack, as shown and described.

DESCRIPTION

FIG. 1 is a front perspective view of a rack in accordance with our new design showing a six-hook style; FIG. 2 is a right side elevational view thereof, the left side elevational view being a mirror image; FIG. 3 is a front elevational view thereof; FIG. 4 is a rear elevational view thereof; FIG. 5 is a top plan view thereof; FIG. 6 is a bottom plan view thereof; FIG. 7 is a front perspective view of a second embodiment of a rack in accordance with our new design showing a ten-hook style, the additional views of this rack being similar to the corresponding views of the first embodiment except for the number of hooks; and, FIG. 8 is a perspective view of a portion of the rack on an enlarged scale.
